DESIGN FOR A GUMMED TAPE DISPENSER

Lyle A. Cheney, Minneapolis, Minn.

Application May 31, 1940, Serial No. 92,700

Term of patent 7 years

To all whom it may concern:

Be it known that I, Lyle A. Cheney, a citizen of the United States and residing in the city of Minneapolis, Hennepin County, State of Minnesota, have invented a new, original, and ornamental Design for a Gummed Tape Dispenser, of which the following is a specification, reference being had to the accompanying drawing, forming a part thereof, wherein,

Fig. 1 is a perspective view of a gummed tape dispenser showing my new design;

Fig. 2 is a top plan view;

Fig. 3 is a side view; and

Fig. 4 is an end view taken from a point at the left of the dispenser as it appears in the other views.

I claim:

The ornamental design for a gummed tape dispenser, as shown.

LYLE A. CHENEY.
